ROTARY TOOL HANDLE AND TOOL THEREFOR

Filed July 7, 1927

Inventor
By James P. Salmon,
Leonard L. Kish
Attorney.

UNITED STATES PATENT OFFICE

JAMES P. SALMON, OF PHILADELPHIA, PENNSYLVANIA

ROTARY TOOL HANDLE AND TOOL THEREFOR

Application filed July 7, 1927. Serial No. 203,944.

My invention relates to a new and useful tool and particularly to a novel combination of a tool handle adapted to receive any one of several forms of rotary tools, such as 5 screw drivers, socket wrenches or the like, and corresponding tools of this character, adapted to coact with said handle, in such a manner as to permit of a ready operative engagement or disengagement of handle and 10 tool, at will, while the tool is being manipulated or used, thereby to produce what is commonly known as a "ratchet effect" between the handle and tool.

My invention further relates to a novel 15 combination of such handle and tool, wherein in the tool may be removed from the handle at will, and another and different tool inserted thereto, so as to be manipulated by said handle in like manner.

With the above ends in view, my invention 20 consists of a suitable elongated tool handle having a polygonal, that is, square or hexagonal aperture or socket therein, preferably at one end thereof. My invention further 25 consists of a tool or a series of tools, each having at one end thereof a suitable tool such as a screw driver, socket wrench or the like, and having at the other end thereof a polygonal shank adapted to be positioned in the 30 polygonal shaped aperture or socket in the handle member at will, thereby to dispose said tool in operatively engaged or disengaged relation to the handle, at will.

My invention further consists of resilient 35 means for normally maintaining said tool and handle in operatively disengaged relation and means for either fixedly or detachably retaining said handle and tool in assembled relation to each other.

For the purpose of illustrating my invention, I have shown, in the accompanying drawings, a form thereof which is at present preferred by me, since it will give, in practice, 45 satisfactory and reliable results, although it is to be understood that the various instrumentalities of which my invention consists can be variously arranged and organized and that my invention is not limited to the precise arrangement and organization of these

instrumentalities as herein shown and described.

Referring to the drawings in which like reference characters indicate like parts,

Figure 1 represents a perspective view of 55 the novel combination handle and tool, embodying my invention.

Figure 2 represents a partial longitudinal section on line 2—2 of Figure 1.

Figure 3 represents a view in elevation and 60 partly in section, of a tool similar to that shown in Figures 1 and 2, of a modified form.

In carrying out my invention, I may provide an elongated handle 1 of any suitable 65 material such as steel, and of any suitable contour, as shown in the embodiment of my invention illustrated in Figures 1 to 3 inclusive, having a socket or aperture 2 extending transversely through one end thereof, of a polygonal cross section or contour, as for instance of a square or hexagonal shape.

The tools 3 or 4, such as a screw driver or 75 socket wrench respectively are each provided, at their ends, with a pair of adjacent and coaxially disposed polygonal and round shanks 5 and 6 respectively. The polygonal shank is of the same contour or cross section as the polygonal socket or aperture 2 in the handle 1, while the round shank portion 6 is 80 of a diameter equal to the diameter of the inscribed circle of the aperture 2, that is, so that the round shank 6 may be rotatably disposed within the polygonal shaped aperture 85 or socket 2.

An annular groove or channel 7 is provided 90 in the uppermost portion of the round shank 6 of the tools 3 or 4.

The handle 1 is further provided with a tool engaging resilient spring member 8, 95 preferably affixed to the handle 1 by screws or other fastening devices 9, extending through the corresponding longitudinally extending elongated apertures 10, in one end of said spring, as shown in Figure 2. The opposed end of the tool engaging spring 8 is provided with a longitudinal slot 11, thereby forming a bifurcated terminal portion. The slot 11 is adapted to engage the 100 annular groove or channel 7 of the tools 3

or 4, so as to establish a locking engagement between the end of the spring and said tool, while permitting the rotation of the latter within said handle 1, as well as with respect to the spring 8.

5 A suitable knob, projection or thumb 12 may be provided on the spring 8 so as to facilitate the sliding or displacement of the spring, when it is desired to insert or remove a tool, 10 into or from the handle 1. Thus, to change the tool in the handle, it is merely necessary to withdraw the spring in the direction of the arrow 13, and to withdraw the tool in the direction of the arrow 14. To insert another 15 tool, the shank of the tool is inserted into the socket 2, and the spring 8 is then moved in the opposite direction, until the bifurcated or slotted portion 11 thereof is seated in the annular groove 7 in the upper most portion 20 of the tool.

Due to the normal position of the spring 8, (shown in Figures 1 and 2,) the tools 3 or 4 will normally be positioned with the round shank 6 thereof disposed in the socket 2. Thus, in the normal position of the tool 3 or 4 with respect to the handle 1, the former is free to rotate within the handle in either direction. After the end of the tool, whether the screw driver 3 or the socket wrench 4, is 25 brought into operative engagement with the screw, bolt-head or nut, which it is adapted to manipulate, the handle 1 is forced down upon the polygonal shank 5, so as to cause an inter-engagement between the polygonal shank 5 30 and the corresponding tool socket 2 in the handle 1, whereupon the deflection of the handle 1 in either direction will cause a corresponding rotation of the tool, since the tool and handle are then locked against any relative rotation with respect to each other. If 35 it is desired to return or deflect the handle back into an initial position, without rotating the tool, the pressure on the handle 1 is relieved, whereupon the spring 8 withdraws 40 the handle in an upward direction relative to the tool 3 or 4, thereby positioning the round shank 6 within the socket 2, so as to permit the relative rotation of the tool and handle. This operation may be effected in 45 either one of two directions.

50 It will thus be seen that by my novel construction, a tool may be provided of a simple and inexpensive, yet efficient form, whereby intermittent rotary motion may be imparted 55 to a tool, in either direction, while the tool is in constant operative engagement with the screw or other element being manipulated, by means of a handle or holder which normally carries the tool in a revolute manner 60 and which can be caused to engage a tool in a non-revolute manner at will.

65 It will now be apparent that I have devised a new and useful rotary tool handle and tool therefor, which embodies the features of advantage enumerated as desirable in the state-

ment of the invention and the above description, and while I have, in the present instance, shown and described a preferred embodiment thereof, it is to be understood that such embodiment is susceptible of variation in various particulars without departing from the spirit or the scope of the invention or sacrificing any of its advantages.

Having thus described my invention, what I claim as new and desire to secure by Letters Patent is:

In a device of the character stated, an elongated handle member having a polygonal shaped socket therein, a tool having two adjacent shanks adapted to be positioned alternatively within said socket, one of said adjacent shanks being round to revolubly fit said polygonal socket, said other adjacent shank being polygonal to non-revolubly fit said polygonal socket, thereby alternatively to dispose said tool in revoluble or non-revoluble relation to said handle member, there being an annular groove in said tool, a generally flat spring slidably mounted upon said handle member, having a bifurcated end adapted revolubly to engage in said corresponding annular groove in the end of said tool when said spring is in its forward or operative position thereby detachably to maintain said tool in assembled relation to the tool holder and normally yieldably to maintain said tool in revoluble relation with respect to the holder member.

In testimony whereof, I have hereunto set my hand.

JAMES P. SALMON.
